METHOD AND APPARATUS FOR REFRIGERATING WITH SOLID REFRIGERANTS

William G. Mayer, Pittsburgh, Pa.

Application June 9, 1932, Serial No. 616,233

5. Claims. (Cl. 62—91.5)

This invention relates to refrigeration, and particularly to the refrigeration of vehicles by means of solid carbon dioxide.

Ordinary water ice as a refrigerant for vehicles, such as trucks, carrying perishable materials, e. g. foodstuffs, is not satisfactory for various reasons. Chief among these are the bulk and weight of ice and brine which must be carried, and the rather limited cooling effect and refrigeration period available. Also, the refrigerating effect is quite restricted.

The advantages of solid carbon dioxide, e. g. in the form of so-called snow or ice, are well known. Its temperature is about -115° F., and it does not melt, but sublimes. It thus provides greater refrigerating possibilities than water ice, and it eliminates the collection of liquid with its attendant disadvantages. In general 1 pound of solid carbon dioxide is capable of the same refrigerating effect as about 15 pounds of water ice. Thus lower temperatures, with better preservation of foodstuffs, are possible, and pay loads and route lengths may be increased. Furthermore, solid carbon dioxide does not require the brines needed with water ice, so that this source of non-pay weight, and the corrosion due to brine, are eliminated.

These properties render solid carbon dioxide an ideal refrigerant, particularly for vehicular transportation of perishables. However, it is substantially more expensive weight-for-weight than water ice; gaseous carbon dioxide formed on evaporation may exert an injurious effect on some foods; and its use requires some measure of temperature control, since otherwise foods refrigerated with it may be frozen. Therefore, trucks and similar vehicles using carbon dioxide refrigerant must be adapted to prevent undue evaporation of the carbon dioxide and contact of the gas with its load, as well as providing for temperature control. The constructions, whether vehicular or stationary, available heretofore have not achieved these ends satisfactorily.

It is among the objects of this invention to provide a method of refrigerating with solid refrigerant which, among other features, is efficient, affords maximum refrigerating effect, and in various aspects of which the rate of heat transfer can be maintained uniform and/or adjusted to suit particular needs, which utilizes the major proportion of the heat absorbing capacity of the refrigerant material, is economical, applicable with particular advantage to vehicle refrigeration, and minimizes disadvantages of prior refrigeration methods.

A further object is to provide an apparatus for refrigerating with solid carbon dioxide, which is compact, of sturdy and inexpensive construction, efficient in operation, adapted for the practice of the method embodied in the invention, and which in a particular embodiment eliminates contact of CO₂ gas with the materials refrigerated.

In accordance with this invention refrigeration of perishable materials disposed in a refrigerating chamber is effected by transferring heat from the chamber directly through a heat exchanging partition of metal of high thermal conductivity to solid carbon dioxide refrigerant in heat-exchanging contact with the other side of the partition. Most suitably the partition constitutes a wall of a container enclosing the refrigerant, and its exterior presents to the chamber a heat exchanging surface of relatively great area while its inner surface most advantageously is adapted to make complete surface contact with the solid refrigerant.

I have found, and the invention is in part predicated on this, that especially desirable results flow from maintaining under pressure in the container the CO₂ gas formed by evaporation of the refrigerant in absorption of heat within the container. This serves to repress evaporation of the solid carbon dioxide, and it increases the efficiency of refrigeration because the cool gas is retained for further heat absorption. The refrigerating efficiency may be, and preferably is, further increased by relieving the excess CO₂ gas into the insulation of the enclosing walls of the refrigerated chamber. In circulating through the insulation the gas absorbs further amounts of heat, so that it approaches atmospheric temperature before finally reaching the atmosphere. This affords utilization of substantially the entire capability of the carbon dioxide to absorb heat; furthermore the transfer of heat from the atmosphere through the enclosing walls of the refrigerated chamber is minimized.

The invention is further predicated upon my discovery that by restricting the heat transfer substantially to the partition, or wall, with which the refrigerant is in contact, evaporation of the refrigerant will be confined primarily to the face in contact with the container wall, so that the refrigerant will continuously present substantially constant refrigerating area. This affords constancy of heat transfer, with consequent uniformity of refrigerating effect and improved efficiency. Also in accordance with the invention regulation of the rate of heat transfer between the chamber and the refrigerant to maintain the

chamber at a desired temperature, is accomplished by interposing resistance to thermal conduction between the refrigerant and the heat exchanging partition.

- 5 The apparatus embodied in the invention comprises a chamber for containing the materials to be refrigerated, preferably one having its enclosing walls insulated with a material permeable by gas. The refrigerant is enclosed with-
10 in a container having a heat exchanging surface of metal of high thermal conductivity exposed to the chamber, and advantageously the container is associated with the top, or roof, of the chamber, with its bottom supporting the refrigerant. Preferably the container is provided externally with a large heat exchanging surface, as by providing it with a plurality of fins or ribs. For most purposes the container is constructed to prevent leakage of substantial amounts of gaseous
15 20 carbon dioxide into the chamber, and most suitably to maintain the evaporated CO₂ gas under pressure, means being provided to relieve excess gas according to circumstances.

Although the exposed walls of the container may act together as a heat exchanging partition, it is preferred, for reasons presently to be explained, to so construct the container as to restrict the heat transfer substantially to the heat exchanging partition, e. g. the bottom wall. In such case the remaining exposed walls are insulated from the refrigerant, but most advantageously they act to assist in absorbing heat from the container, and to transfer it to the heat exchanging wall.

35 The invention is particularly adapted for use with trucks and other vehicles and for purposes of further illustration will be so described, although it will be understood that it is not restricted thereto and may be applied to other uses.

40 In the accompanying drawings Fig. 1 is a fragmentary side elevation, partly in section, of a truck body showing one embodiment of the invention; Fig. 2 an enlarged horizontal view, partly in section, of the refrigerant container taken 45 on line II—II, Fig. 1; Fig. 3 a perspective view of the container shown in Figs. 1 and 2; Fig. 4 a perspective view of an insulating pad for use in the practice of the invention; Fig. 5 a bottom plan view of another form of refrigerant container illustrating the preferred embodiment of the invention; Fig. 6 a sectional view through the container shown in Fig. 5, taken on line VI—VI thereof; Fig. 7 a horizontal section through one 55 end of the container shown in Figs. 5 and 6, illustrating details of the door assembly; and Fig. 8 a cross section through the door shown in Fig. 6, taken on line VIII—VIII, illustrating further details of the door construction.

50 Referring to Figs. 1 to 3, a truck chassis 1 is provided with a body having double walls 2 enclosing a refrigerating chamber 3. The space between walls 2 is filled with suitable heat insulating material 4, preferably one permeable by gas, such as the fibrous insulators now commonly used for instance "Kapok" or "Balsa wool." As shown in Fig. 1, a refrigerant container 5 is mounted in a hatchway formed in the roof of the truck body. Container 5 comprises a base plate 6, which supports a cake 7 of solid carbon dioxide within the container, and which is connected to vertically positioned side plates 8. Plates 6 and 8 are formed from a metal of good thermal conductivity, such as aluminum or its light alloys. Advantageously the cross sectional dimensions of the container are such as to accom-

modate the standard cakes of solid carbon dioxide, or multiples or uniform fractions thereof. The container is suspended from the side walls 9 of the hatchway, and in the embodiment shown the container is constructed and is fitted into the hatchway snugly to prevent leakage of substantial amounts of gas into the compartment.

5 Base plate 6 is preferably provided with means for increasing its normal heat radiating capacity, 10 and this may be accomplished by connecting to one or both sides of the base plate sheet metal corrugated to form V-shaped fins. As shown in Figs. 1 and 2, the lower side of the base plate is provided with corrugated sheets 11 forming ribs 15 which extend entirely across the lower side of the base plate, the latter extending laterally from the sides 8 to increase the heat exchanging surface. The lateral projections of plate 6 are provided on the upper surface with similar corrugated sheets 12, as shown particularly in Fig. 2. This construction provides channels for circulation of air over the heat radiating surfaces, so as to increase the rate of heat transfer. Such air circulation may be increased by perforating 20 corrugated sheets 11 and 12 as at 13 and by cutting slots 14 through the sheets and plate 6.

25 The construction thus provided is adapted to efficiently refrigerate the compartment. In most instances regulation of temperature is desirable, 30 however, either to prevent freezing of the materials carried in the truck, or to keep them at a desired optimum temperature, and also to minimize CO₂ consumption. Such control may be effected by vertical adjustment of the container 35 in the hatchway, or of the refrigerant in the container, or both. The container position may be adjusted by moving it up or down in the hatchway, a plurality of horizontal rows of screw holes 15, Fig. 3, being provided in walls 8 for 40 that purpose.

30 Further control of rate of heat transfer is afforded by interposing thermal resistance under the refrigerant. The pad shown in Fig. 4 forms a particularly suitable means of doing this. It 45 comprises a hollow box-like structure 16 formed of metal, the interior being reinforced by corrugated sheet metal 17 to resist crushing of the walls by the refrigerant cakes. The heat insulating effect may be increased by making the box 50 gas tight to provide dead air space. Being formed from metal and being in full contact with cake 7 such pads afford direct heat transferring contact between the refrigerant and base plate 6, while they reduce the rate of heat 55 transfer.

35 I have found that particular advantages attend the retention under pressure in the container of the gaseous CO₂ which is formed as the solid refrigerant evaporates in absorbing 60 heat from the compartment. To this end the container and its associated parts are constructed to maintain the gas under a desired pressure. For this purpose hatchway cover 10 is maintained by any suitable means in gas-tight relationship 65 with the hatchway. For example to each side of the cover there is connected a spring latch 18 which engages a catch 19 mounted on side wall 9. The latches press the cover against a gasket 20 interposed between the cover and the top of 70 the hatchway.

40 Excess pressure is relieved through an outwardly opening adjustable relief valve indicated schematically at 21, a number of types of which are available. Because the CO₂ gas formed in 75

the container is quite cold it is preferred to relieve it into insulation 4, so as to obtain additional refrigerating effect. Thus valve 21 opens into the insulation space between side walls 2 so that the gas circulates through insulation 4, thus cooling the compartment walls and minimizing heat transfer to the chamber from the atmosphere. In order to permit free circulation through the insulation body structural members, such as indicated at 22, are provided with holes 23 as need be. The gas finally escapes to the atmosphere through the cracks in the body walls. The refrigerating unit thus provided possesses numerous advantages, among which are its compactness, the slight weight of the container and refrigerant needed to equal the refrigerating effect of large volumes and weights of water ice, and the ability to prevent contact of foodstuffs with gaseous CO₂.

Especially great advantages flow from the efficiency of the unit, which arises from a number of factors. In the first place, the heat transfer is directly from the chamber through the heat exchanging wall to the refrigerant. This is augmented by presenting a large heat absorbing surface to the chamber, and by having the refrigerant cake in full contact with the other side of the exchanging wall, i. e. having a flat surface of refrigerant entirely contacting the plane surfaced base.

Further efficiency is derived from the ability to regulate the rate of heat transfer, so that the refrigerant is not used needlessly, and so that the refrigeration is optimum for the particular materials being cooled. Thus if the heat exchanging surface is too great for the refrigeration desired, the container may be moved upwardly in the hatchway, to reduce the rate of heat transfer, and vice versa. A similar result is obtained by the use of thermal resistance between the plate and cake 7. The pads described are especially desirable, as they maintain metallic and full contact between the plate and the refrigerant, and merely reduce the rate of heat transfer to the base and the area of refrigerant exposed to the side walls. Both means of adjustment may be used, for example to roughly approximate the desired temperature by varying the container position, and completing the regulation by the use of pads. Actual tests have shown that in this manner desired temperatures in the range from 40° F. below zero to 15° F. above zero can be maintained satisfactorily.

Absorption of heat from the chamber causes formation of CO₂ gas, and this is used in two ways to appreciably augment the refrigerating effect. By retaining the gas under pressure it is available for further absorption of heat, and it represses evaporation thereof, thus decreasing the consumption of solid carbon dioxide. In general, retention of the gas at pressures of from about 5 to 15 pounds per square inch affords satisfactory results. Second, ancillary cooling is obtained through release of gas to the enclosing walls when the pressure within the container builds up to a point where it exceeds the pressure for which the relief valve is set. The cool gas circulates through the insulation around the enclosing walls, and this may be, and advantageously is, enhanced by sealing the linings of the inside and outside walls, and roof, of the vehicle body, so as to compel the gas to flow over the roof and sides before it can escape to the atmosphere. Thus the gas cools the body walls,

and this further reduces refrigerant consumption, so that substantially the full refrigerating power of the CO₂ is thereby utilized. In addition, this circulation of gas through the enclosing walls serves the useful function of keeping the insulation dry, the gas flow preventing entry, or at least accumulation, of atmospheric moisture.

In case insulation 4 is not a fibrous or loose and gas permeable material, the relief valve 10 may open to the atmosphere, or where meat and the like goods, which are improved, or whose value is not deteriorated, by carbon dioxide gas, are carried the valve may open directly into the compartment, if desired.

The preferred embodiment of the invention is illustrated in Figs. 5 to 8, according to which the refrigerant container is mounted wholly within the chamber to be refrigerated. In this embodiment the container comprises a shell, or box-like structure, advantageously of cast construction, having a base 25, side walls 26, and a top 27. The container is provided with a door, for introducing refrigerant; preferably it forms one end of the container, the opposite end being closed by a wall 26a continuous with side walls 26. The container is attached in any suitable manner to the top of the chamber to be refrigerated, for example by lag screws 27a, Fig. 6. Solid carbon dioxide refrigerant 1a rests in 30 complete contact with bottom wall 25, as in the preceding embodiment. In order to increase the heat exchanging area exposed to the chamber, the bottom wall is provided with integrally cast longitudinal and transverse fins, or ribs, 28 and 29, respectively.

An adjustable automatic pressure relief valve 21a is connected to a boss 30 formed on one side of the container for the purpose described hereinabove, and the door is arranged to be 40 gas tight under the pressures used. Various constructions may be used for this purpose, but I have found that, in general, the pressure within the container tends to cause leakage around the periphery of the door unless it is of very 45 heavy section, or unless it is designed to prevent its being sprung by the pressure within the container.

A door construction which has been found to be satisfactory is illustrated in Figs. 7 and 8. As 50 there shown the door comprises a peripheral flange 31 conforming to the end of the container, and an integrally formed body portion 32 which is bowed outwardly, as seen in Fig. 8. This shape resists deformation by interior pressure, but to 55 further reinforce it the door is provided internally with longitudinal ribs 35.

The door is hinged to swing at bottom wall 25 of the container by hinge connections 350; 60 Figs. 5 and 8, and it is clamped in closed position by a cross yoke 36 held pivotally by a pin 37 in a U-bracket 38 integral with and projecting from the face of the door. The door is forced into sealing relationship with a gasket 39 surrounding the container by application of pressure to the ends of yoke 36 through pressure screws 40 which move in threaded U-shaped bracket members 41 pivotally connected by pins 42 to bosses 43 cast integrally at the sides of the container. To remove the door, screws 40 are backed off sufficiently to permit brackets 41 to be swung laterally, thus freeing the yoke and door. Prior to opening the door the gas pressure is relieved through a hand operated blow-off valve 44 pass- 75

ing through a boss formed on one side of the container.

The container just described may be used to effect refrigeration of the chamber within which it is mounted, e. g. a truck body, by transfer of heat from the chamber through the bottom and side walls of the container, as in the preceding embodiment. But where heat is transferred freely through all sides of the container, as in prior units, the solid refrigerant diminishes in size in all of its dimensions. This decreases the area of contact of the refrigerant with the container wall, and may result in decreasing rate of heat transfer.

In a further aspect of the invention I have found that adequate and uniform refrigeration may be obtained by substantially restricting heat transfer to the wall of the container with which the refrigerant is in contact, which I have found maintains substantially constant contact area between the refrigerant cake and the heat exchanging partition. This is accomplished, as shown in Fig. 6, by mounting an inner liner 45 of wood or other material of low heat conductivity within the container to form a space between it and the side walls and top. This space is lagged with a heat insulator 46, such as cork or the like. The door is likewise insulated by a panel 460 of suitable wood. To increase the area of the heat exchanging surface, to provide adequate refrigerating effect for all conditions, the sides and ends of the container are provided with fins 47 cast integrally with the container. These fins act chiefly to augment the absorption of heat, which they transfer to the base, for the insulation of the top, side and end walls prevents direct transfer of heat from them to the refrigerant. It is preferred that the total exposed area of the container, i. e. the surface area of the fins plus the surface area of the walls between the bases of the fins, be at least equal to the area of the roof plus half the area of the enclosing walls, as this gives the most satisfactory results for most purposes.

It thus appears that in the preferred embodiment fin sides of the container act to absorb heat and transfer it through a single side to the refrigerant, which is insulated on fin sides, and further that the enclosing walls are refrigerated on fin sides by the evaporated gas. Tests of a refrigerant container constructed in this manner have shown that in actual service cake 1a diminishes in size primarily in its horizontal dimension. That is, the area of contact with base 25 remains substantially constant, the cake gradually decreasing in height without materially diminishing in horizontal cross sectional area. Thus restriction of heat transfer substantially to the contact surface maintains a substantially uniform area of contact between the cake and bottom 25 and provides practically constant heat exchanging conditions.

The retention of CO₂ gas under pressure results in the same advantages as described in the preceding embodiment. In the embodiment last described the rate of heat transfer may be altered according to need, e. g. by interposing resistance to heat transfer, as by means of pads 16.

The preferred embodiment has the advantage that it is mounted totally within the chamber, which eliminates the necessity for cutting holes through the roof, and eliminates the protruding hatchway, which may be unsightly and otherwise disadvantageous in truck construction. The door is advantageously positioned facing the door

of the truck body, so that the refrigerant may be readily introduced into the container.

The invention thus provides for adequate and efficient refrigeration of chambers containing perishable materials. The apparatus provided by the invention and used in the practice of its method requires but a small amount of space in the refrigeration compartment. This provides greater refrigerating space, and consequently larger pay loads. Furthermore, as the unit is relatively small, and is preferably constructed from a light metal, lighter trucks can be used, which decreases the initial vehicle cost and its upkeep, and also increases the area of the district that can be served by a single vehicle. The corrosion due to the use of water ice is eliminated. The refrigeration is improved, being uniform and otherwise more desirable than that with water ice. Substantial economies attend the use of evaporated gas in the manner described, because this utilizes as completely as is economically possible the heat absorbing capacity of the refrigerant. Other advantages will be understood by those skilled in the art.

Actual experience with units embodying the invention has clearly demonstrated its utility, both in effecting quick cooling of the chamber, and maintaining adequate refrigeration, and in providing economy of refrigerant. The value of circulating the gas through the enclosing walls is shown in part by the fact that frost may, and does, appear on the ceiling and walls for a substantial distance from the unit, or container. This shows the gas to be very cold as it leaves the container, and that this factor substantially reduces the transfer of heat to the chamber from the atmosphere, and that in turn reduces solid CO₂ consumption.

The invention is not restricted to use with trucks, but is applicable to other vehicles, such as railway or freight cars, and also to stationary refrigeration, as of cabinets and permanent and fixed refrigerating installations.

This application is a continuation in part of my copending application Serial No. 534,721, filed May 4, 1931.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A bunker for solid carbon dioxide refrigerant comprising a metallic container having top, bottom and side walls of a metal of high thermal conductivity associated in gas-tight relation, said bottom wall being ribbed to provide a total exposed heat exchanging area at least equal to the area of the roof and one-half the side walls of the chamber to be refrigerated, one of said container walls providing an aperture for introduction of said carbon dioxide, and a closure for said aperture comprising an outwardly bowed member, a yoke adapted to press said member into gas-tight relation with the sides of the aperture, and releasable means associated with said container cooperating with the yoke to effect closure.

2. A bunker for solid carbon dioxide refrigerant comprising a metallic container having top, bottom and side walls of a metal of high thermal conductivity associated in gas-tight relation, the bottom wall being ribbed to provide a total ex-

- posed heat exchanging surface equal at least to the area of the roof plus one-half the side wall area of the chamber to be refrigerated, one of said container walls having an aperture for introduction of said carbon dioxide, and a closure for said aperture comprising an outwardly bowed plate member, a yoke adapted to press said member into gas-tight relation with the sides of the aperture, and releasable means associated with said closure cooperating with the yoke to effect closure.
4. A bunker for solid carbon dioxide refrigerant comprising a metallic container having a top wall for association with the roof of the chamber to be refrigerated, side walls, and a bottom wall ribbed exteriorly to provide a total exposed heat exchanging area at least equal to the area of the roof plus one-half the area of the side walls of the chamber to be refrigerated, said container being formed of metal of high thermal conductivity and the walls being associated in gas-tight relation with one another with one side wall providing an aperture for introduction of refrigerant, said container side walls being interiorly insulated, and a closure for said aperture comprising an outwardly bowed plate member, a bowed yoke adapted to press said closure into gas-tight relation with the sides of the container, and releasable means associated with the container operating with the yoke to effect closure.
5. A bunker for solid carbon dioxide refrigerant according to claim 4, and an outwardly opening relief valve associated with one of the container walls for retaining CO₂ gas therein under predetermined pressure.
3. A bunker for solid carbon dioxide refrigerant comprising a metallic container having a top wall for association with the roof of the chamber to be refrigerated, a bottom wall and side walls, said walls being formed of metal of high thermal conductivity associated in gas-tight relation with one another and one of the side walls providing an aperture for introduction of refrigerant, said side walls being interiorly insulated, and a closure for said aperture comprising an outwardly bowed plate member, a bowed yoke adapted to press said closure into gas-tight relation with the sides of the aperture, and releasable means associated with

WILLIAM G. MAYER.
